[57] CLAIM

The ornamental design for an electrical bracket for an airplane, as shown and described.

DESCRIPTION

FIG. 1 is a top plan view of an electrical bracket for an airplane showing my new design;

FIG. 2 is a bottom plan view thereof;

FIG. 3 is a right side elevational view thereof, the left side being a mirror image thereto;

FIG. 4 is a front elevational view thereof;

FIG. 5 is a rear elevational view thereof; and,

FIG. 6 is a perspective view thereof showing use of my new design in an airplane.

The broken line showing of the control knobs in FIGS. 4 and 6 and the interior of an airplane in FIG. 6 is for illustrative purposes only and forms no part of the claimed design.
